W. J. Bissell
ATTORNEY

UNITED STATES PATENT OFFICE.

CHARLES FISCHER, OF NEW YORK, N. Y.

TAKE-UP SPRING.

Application filed September 17, 1924. Serial No. 738,321.

To all whom it may concern:

Be it known that I, CHARLES FISCHER, a citizen of the United States, a resident of New York city, in the county and State of 5 New York, have invented certain new and useful Improvements in Take-Up Springs, of which the following is a specification.

My invention relates to take-up springs for electric cords used for electrical appliances, such as table lamps, electric irons and the like, and more particularly to a take-up spring which can be attached to the intermediate portion of a cord provided with connector plugs at the ends. The invention is 10 especially useful in connection with taking up the cord of an electric iron, thus doing away with the inconvenience and annoyance of having the cord in the way of the iron when the latter is in use and permitting free 15 use of the iron by the operator.

One of the objects of my invention is to provide a helical take-up spring with wire and gripping means forming part of the ends of the spring for gripping the ends to 20 the cord.

Another object of my invention is to provide a wire helical take-up spring with its wire ends preformed into a plurality of two or more separated, gripping loops, thereby 25 directing the gripped portion of the cord at an angle to the longitudinal axis of the body of the spring and thus improving the gripping action.

Another object of the invention is to provide the gripping ends with means for attaching them to an intermediate portion of the cord and at any desired place thereon and, if desired, while the cord is in position. This may be accomplished without removing 30 the plug ends from the cord. The yielding 35 spring in addition to taking up the slack will yield when the position of the electrical apparatus such as an iron, is shifted.

With the above and other objects in view, 40 my invention consists in the parts, improvements and combinations more fully pointed out hereinafter.

Referring now to the drawings:

Figure 1 is a perspective view showing the 45 take-up spring in use with the cord attached to an electric iron.

Figure 2 is a front elevation, about full size, of the form of spring take-up shown in Figure 1.

Figure 3 is a top plan view looking down

at one end of the spring shown in Figure 1, and

Figure 4, is a front elevation showing another form of take-up spring attached to a cord.

In the drawings an electric cord 1 having end plugs 2 and 3 is shown attached to an electric socket 4 at one end and to an electric iron 5 at the other end. The helical coiled spring 6 is formed of sufficient turns 50 65 70 of wire to make it strong enough to support the loop of the electric cord and to yield under the pull of use. Each end of the wire of the spring is shaped during its manufacture into a plurality of loops which 75 grip the cord. These loops 8 and 9 are two in number in the form of the invention shown in Figures 1 to 3 and may be as high as five or more in number as shown in the form illustrated in Figure 4. The wire 80 tongues 10 separate the loops in the first form. The wire end of the spring is thus preformed into two loops separated by the tongue and its distal end is looped at 10^a around the end turn of the body portion of 85 the spring. The tongue projects toward the end turn of the spring leaving a space 11, thereby enabling the cord to be inserted into the wire looped end. Means are thus pro- 90 vided for attaching the ends to an intermediate portion of the cord at any desired place thereon. It will be observed that the wire loops 8 and 9 in Figures 1 to 3, lie in the same plane and that the cord passes thru them cross-wise of the axis of the helical 95 body of the spring. The cord is thus compelled to change its path, at each end of the spring and may make a substantially right-angled turn. The cord also passes in a bent or curved path about the tongue as shown in 100 Figure 3, the tongue because of its spring action helping to bind the cord in the loops. The cord is thus frictionally and yieldingly gripped by the ends of the spring so that the 105 amount of slack of the cord to be taken up may be readily adjusted and the spring secured to any desired part thereof. When in use with an electric iron as illustrated, the user presses the spring ends over the cord, taking up the desired amount of slack, and when ironing the spring will yield as shown in Figure 1, without pulling the cord thru the gripping ends, thus allowing the iron 5 to be moved over the work on the board 12.

In the form of the invention shown in 110

Figure 4, the loops 13 of the spring 14 are preformed in the wire ends during the manufacture of the spring, the loops being separated from each other and extending crosswise or at an angle to the axis of the spring 14. The separation of the loops permits the slack of the cord 15 to be inserted thru them without removing the plugs from the cord. As the cord bends the loop ends 10 the frictional yielding grip of the ends on the cord is increased. The cords are kept at an angle crosswise of the axis of the body of the spring, which helps to increase the grip. In both forms of the invention, the 15 ends and the body of the spring consist of a single piece of wire.

Having thus described the invention, it will be understood that changes may be made in the construction for carrying the 20 invention into effect, without departing from the principle thereof.

What I claim is:

1. An electric cord take-up consisting of a helical wire spring having wire ends, the 25 said wire ends being shaped to provide a plurality of gripping loops for gripping the ends to the cord, which passes thru them.
2. An electric cord take-up consisting of a helical spring having a body portion and 30 having yielding wire and loops for gripping the ends of the cord, which passes thru them, said end loops extending cross-wise of the axis of the body of the spring.
3. An electrical cord take-up consisting of

a helical wire spring having a body portion, 35 each wire end thereof being coiled into a plurality of preformed, separated gripping loops thru which the cord passes, said gripping loops extending cross-wise of the axis of the body of the spring.

4. An electrical cord take-up consisting of a helical wire spring, each end thereof being coiled into two preformed gripping loops, the said loops being separated by a wire tongue.

5. An electrical cord take-up consisting of a helical wire spring, each end thereof being coiled into two preformed gripping loops, the said loops being separated by a wire tongue, the said tongue projecting toward but being separated from the end of the spring.

6. An electrical cord take-up consisting of a helical wire spring, each end thereof being coiled into two preformed gripping loops, the said loops being separated by a wire tongue, the distal end of the looped ends being connected to the end turn of the body of the spring.

7. An electrical cord take-up consisting of a helical wire spring, each end thereof being coiled into two preformed gripping loops, the said loops being separated by a wire tongue, the said two loops lying in the same plane.

In testimony whereof, I have signed my name to this specification.

CHARLES FISCHER.
